[57] CLAIM

The ornamental design for a wall mounted lighting fixture, as shown and described.

DESCRIPTION

FIG. 1 is an elevational view of one end of the wall mounted lighting fixture of the present invention, the opposite end being a mirror image;

FIG. 2 is an elevational view of the front of the lighting fixture of the present invention;

FIG. 3 is a top view of the wall mounted lighting fixture of the present invention;

FIG. 4 is a perspective view of the wall mounted lighting fixture of the present invention;

FIG. 5 is a horizontal cross-sectional view of the wall mounted lighting fixture of the present invention as taken along line 5—5 of FIG. 1; and,

FIG. 6 is a vertical cross sectional view of the wall mounted lighting fixture of the present invention as taken along line 6—6 of FIG. 3.

FIG. 2

FIG. 3

FIG. 1
